(57) **CLAIM**

The ornamental design for false eyelashes, as shown and described.

DESCRIPTION

FIG. 1 is a front, right and top perspective view of false eyelashes, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed broken lines depict portions of the false eyelashes that form no part of the claimed design.

1 Claim, 8 Drawing Sheets
